CIGARETTE CASE

Peter Honcharenko, 4071 Glendale, Detroit 38, Mich.

Filed July 3, 1958, Ser. No. 746,505

3 Claims. (Cl. 221—232)

This invention relates to improvements in cigarette dispensing cases for carrying in a pocket, a pocketbook, or the like.

The primary object of the invention is to provide a cigarette case embodying cigarette ejecting means readily operative by the thumb of one hand grasping the case, whereby cigarettes may be ejected out of the case and placed directly from the case into the mouth without either hand touching the cigarettes and possibly contaminating the dispensed or ejected cigarette by handling the same. This is especially advantageous to automobile drivers and persons engaged in unsanitary work and to workmen having one hand continually in use while working.

Another object is to provide a cigarette case for the above purposes which is easy to refill, without damaging the cigarettes and in which the ejecting means will not jam nor tear the cigarette paper, and which is of simple, inexpensive and durable construction.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the case;

Figure 2 is an enlarged view in side elevation of a cigarette container forming part of the case;

Figure 3 is a view in vertical longitudinal section of the case;

Figure 4 is a view in vertical cross-section taken on the line 4—4 of Figure 3;

Figure 5 is a view in vertical cross-section taken on the line 5—5 of Figure 3;

Figure 6 is a view in vertical cross-section taken on the line 6—6 of Figure 3;

Figure 7 is an enlarged perspective view of an ejector slide forming part of the ejecting means, and

Figure 8 is an enlarged fragmentary view in vertical longitudinal section of one corner portion of the case.

Referring to the drawings by numerals, the cigarette case, designated generally by the numeral 1, comprises, as its basic components, a flat, open top, rectangular cigarette container 3, and a flat, open bottom, rectangular cover 5 for the container 3 fitting with a slip fit downwardly over said container.

The container 3 comprises side walls 7 spaced apart to accommodate therebetween a single layer stack of cigarettes 9, front and rear end walls 11, 13 spaced apart a distance corresponding, approximately, to the length of the cigarettes 9, and a bottom wall 15 forming a trough 17 between the end walls 11, 13 for seating the cigarettes 9 successively of the stack in position for ejection successively forwardly out of the case 1, in a manner presently clear.

The side walls 7, which are integral with the bottom wall 15, are provided with vertical central slots 21 through

2

which the fingers of a hand may be inserted in loading or filling the container 3 with a stack of cigarettes 9, and the front end wall 11, which is also integral with the bottom wall 15, is provided with a bottom discharge opening 23 aligned with the trough 17 for ejection of cigarettes out of the trough 17 forwardly of the container 3.

The rear end wall 13 of the container 3 is formed of front and rear sections 25, 27 spaced apart to provide a vertical slot 29 in said rear end wall 13 open at the top and bottom of the container 3, the front section 25 being spaced above the trough 17 and the rear section 27 being removably secured to the side walls 7 for access to the slot 29, by cross-pins 31, all for a purpose presently apparent.

The cover 5 comprises side walls 33 and front and rear end walls 35, 37 and fits downwardly over the container 3 with its bottom edge substantially flush with the bottom face of the bottom wall 15 of the container 3. A cigarette discharge bottom opening 39 is provided in the front end wall 35 of the cover 5 to register with the opening 23, when the cover 5 is applied, for ejection of cigarettes outwardly of the case 5.

The ejecting means comprises the following: An elongated manually operative ejecting slide 41 is guidingly mounted on the underside of the bottom wall 15 for advance from a retracted position longitudinally of said wall 15 to engage an upstanding pusher finger 53 on said slide with the butt end of a cigarette 9 in the trough 17 to eject the cigarette. The slide 41 has a serrated bottom face 55 depending below the bottom wall 15 for non-slip engagement of the thumb of a hand with said slide to advance the same, and is guidingly mounted for advance and retraction by means of longitudinal tongues 57 thereon sliding in longitudinal grooves 59 in the bottom wall 15 which are open at the rear end wall 13 for insertion of said slide 41 in place when the rear section 27 of the rear end wall 13 is removed. Retraction of the slide 41 is limited by said rear section 27.

The pusher finger 53 is advanced and retracted by the slide 41 in a longitudinal slot 61 in the bottom wall 15, through which it projects upwardly out of the trough 17, and when retracted is disposed under the front section 25 of the rear end wall 13. Advance of the pusher finger 53 and consequently of the slide 41 is limited by engagement of said finger 53 with the front end of the slot 61. The pusher finger 53 is stepped, as at 63, to seat and support thereon the butt end of a cigarette 9 in the trough 17.

Spring means is operatively connected to the pusher finger 53 to retract the same and the slide 41 and comprises the following: A helical spring 65 in the slot 29 of the rear end wall 13 depends from and is suitably connected at its upper end to a cross-pin 67 in said slot.

55 A pull cord 69 is terminally connected to the lower end of the spring 65, as at 71, and to the pusher finger 53, as at 73, and is slidably trained under a cross-pin 75 in the lower end portion of said slot 29.

Follower means is provided for the stack of cigarettes 9 for urging the same successively into the trough 17. This means comprises an elastic band 77 looped through a transverse bottom groove 79 in the rear section 27 of the rear end wall 13 from which it extends forwardly at opposite sides of the bottom wall 15 in grooves 81 in said wall 15 and is trained under and upwardly around a transverse headed pin 83 in said wall 15 to extend upwardly in the slots 21 in straddling relation to the stack of cigarettes 9. The pin 83 is preferably formed of telescoped male and female sections 85, 87.

70 The sides of the bottom wall 15 are recessed, as at 89, with countersinks, as at 91, therein to accommodate the

sides of the elastic band 77 and the heads of the pin 83 all of which together with the grooves 79, 81 and the slots 21 prevent the elastic band 77 from projecting outwardly beyond the sides of the container 3 and thereby interfering with applying the cover 5.

The use and operation of the described invention will be readily understood. To load or fill the case 1, the cover 5 is removed from the container 3 after starting the same by inserting a fingernail under the lower front corner 89a and in a transverse front, bottom corner notch 93 in the bottom wall 15. After the cover 5 is removed, the elastic band 77 is pulled upwardly and forwardly and looped into an upper corner, transverse notch 97 in the front end wall 11 of the container 3 so that said elastic band is inclined forwardly and upwardly out of the slots 21, as shown in broken lines in Figure 2, out of interfering position with filling the container 3 by fingers inserted downwardly through the slots 21. The cigarettes 9 are then stacked in the container 3 one on top of the other after which the elastic band 77 is released or pulled upwardly out of the notch 97 and then backwardly into straddling relation to the stack of cigarettes 9, as best shown in full lines in Figures 2 and 6. The cover 5 is then applied to the container 3.

With the case 1 filled, as described, it may then be grasped between the index and second fingers of a hand and with the thumb of the hand engaged beneath the serrated bottom face 55 of the ejecting slide 41 said slide may then be advanced, in opposition to the spring 65, to advance the projector finger 53, as shown in broken lines in Figure 3, whereupon said finger will engage the butt end of the lowermost cigarette 9 of the stack, which is in the trough 17, and eject the cigarette partway out of the openings 23, 39, as shown in broken lines in Figure 2, for insertion in the mouth of a smoker to be grasped by the lips to pull said cigarette completely out of the case 1. Thus, as will be seen, a cigarette may be obtained from the case 1 for smoking by the smoker using one hand only to operate and manipulate the case 1 and without touching, with the hand, the cigarette obtained from the case.

The case 1, with the exception of the elastic band 77, may be formed of any suitable material. The elastic band 77 is preferably, although not necessarily, an ordinary rubber band of suitable size.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may

be resorted to, falling within the scope of the invention as claimed.

What is claimed as new is as follows:

1. A pocket cigarette case comprising an open top rectangular receptacle having front and rear end and side walls respectively, and a bottom wall forming a bottom trough for containing the bottom one of a stack of cigarettes placed in the receptacle, an open bottom rectangular cover slidably fitting downwardly over said receptacle and having a front wall, said front walls having registering cigarette discharge openings therein in line with said trough, said bottom wall having a longitudinal slot therein and said rear end wall having a longitudinal slot therein opening into said longitudinal slot in said bottom wall, an ejector slide beneath said bottom wall mounted thereon for advance and retraction, a pusher finger on said slide extending into said longitudinal slot therein for advance by said slide against one end of a cigarette in said trough to eject said cigarette outwardly of said openings, spring means in the longitudinal slot in the rear end wall extending into the longitudinal slot in the bottom wall and connected to said slide to retract the same, and resilient follower means for a stack of cigarettes extending from said rear end wall alongside said bottom wall and over a stack of cigarettes in the container for urging said stack toward said trough, said spring means comprising a helical spring terminally attached in the longitudinal slot in said rear end wall, and a pull cord terminally attached to said spring and extending into the longitudinal slot in the bottom wall and attached to said slide, said rear end wall including an external removable section exposing when removed the slots in said bottom and rear end walls for access to said spring and pull cord to renew the same.
2. The combination of claim 1, said resilient means comprising an elastic band arranged to loop over said stack transversely of the sides of the cigarettes.
3. The combination of claim 2, the side walls of said container having slots therein for accommodating said band for looping over the stack and exposing to view the cigarettes in the stack.
